UNITED STATES PATENT OFFICE.

ORLANDO B. STRICKLAND, OF ELYRIA, OHIO, ASSIGNOR OF ONE-HALF TO ALBERT N. LYBERGER, OF ELYRIA, OHIO.

DESIGN FOR A ROCKING CHAIR.

Application filed January 24, 1923. Serial No. 4,981. Term of patent 7 years.

To all whom it may concern:

Be it known that I, ORLANDO B. STRICKLAND, a citizen of the United States, residing at Elyria, in the county of Lorain and State of Ohio, have invented a new, original, and ornamental Design for Rocking Chairs, of which the following is a specification, reference being had to the accompanying drawing, forming a part thereof.

ing chair looking at the front, showing my new design;

Figure 2 is a perspective view of the same looking at the rear.

I claim:

The ornamental design for a rocking chair substantially as shown.

In testimony that I claim the foregoing as my own, I have hereto affixed my signature.

ORLANDO B. STRICKLAND.
